SASH TIGHTENER

Harry D. Sevison, Elkhart, Ind., assignor to The Adlake Company, Chicago, Ill., a corporation of Illinois

Application December 13, 1930
Serial No. 502,076

8 Claims. (Cl. 189—73)

The ordinary car window is hard to open, due to the fact that it is purposely given a tight fit in order to make it waterproof around the edges.

The principal object of this invention is to provide an improved window for railway cars, buses and the like which can be opened and closed easily, is absolutely water-tight when closed, and can be manufactured at but little additional cost.

10 Other more specific objects and advantages of the invention will be apparent to those skilled in the art upon a full understanding of the construction, arrangement and operation of the improvement constituting the invention.

15 Two different forms of the invention are presented herein by way of exemplification, but it will of course be appreciated that the invention is capable of embodiment in other structurally modified forms coming equally within the scope 20 of the appended claims.

25 In the accompanying drawings:

Fig. 1 is an inside face view of a window equipped with a pair of the new sash tightening devices;

28 Fig. 2 is a horizontal section through one side of the window, taken on the line 2—2 of Fig. 1;

Fig. 3 is a vertical section through the same side of the window, taken on the line 3—3 of Fig. 2, showing the sash closed and the tightening member at that side of the window in its laterally projected position;

35 Fig. 4 is a sectional view corresponding to Fig. 3, showing the sash raised up off of the sill and the tightening member in its laterally retracted position;

Fig. 5 is a vertical section, taken on the line 5—5 of Fig. 1, showing the projected position assumed by each of the tightening members when the sash is closed;

40 Fig. 6 is a sectional view corresponding to Fig. 5, showing the retracted position assumed by each of the tightening members when the sash is raised up off of the sill;

Fig. 7 is another vertical section, taken on the line 7—7 of Fig. 6;

45 Fig. 8 is a horizontal section through one side of a window, showing a different form of the invention;

Fig. 9 is a vertical section, taken on the line 50 9—9 of Fig. 8, showing the sash closed and the tightening member projected; and

Fig. 10 is a sectional view corresponding to Fig. 9, showing the sash raised and the tightening member retracted.

55 The form of the invention illustrated in Figs.

1 to 7 inclusive will first be described. In these views, a sash 10 is shown positioned in a frame 11, with the sides 12 of the sash slidably mounted in vertical guide grooves 13 formed between projecting portions 14 of the sides 15 of the frame and detachable guide strips 16. The sides 12 of the sash fit rather loosely in the grooves 13, thereby permitting free up and down sliding movement of the sash, and are provided on their outer faces with sealing strips 17 made of pile 65 fabric, felt or other suitable material, which sealing strips are adapted to engage and seal with the opposed walls 18 of the projecting portions 14 of the frame when the sash is in its lowermost position. The top rail 19 of the sash 70 is provided on its outer face with a sealing strip 20, similar to the strip 17, for engagement with the header 21 of the frame, while the bottom rail 22 of the sash is provided at its lower edge with a rubber sealing strip 23 for engagement 75 with the sill 24 of the frame.

The sides of the sash, which are hollow, house a pair of automatically functioning tightening devices 25. Since both of the devices are the same, only one will be described in detail. It 80 consists of a small finger 26 which is pivoted at 27 to a vertically movable carrier block 28. The block 28 is pressed downwardly by a coil spring 29 which is compressed between a flange 30 on the top of a stationary reinforcing channel 31 in the 85 sash and an abutment 32 on the top of a U-shaped strap 33 attached to the sides of the block. The channel 31 supports a cam block 34 which is positioned between the spaced sides of the strap 33 beneath the abutment 32 and above the finger 90 26. The lower end of the cam block 34 is beveled at 35 and the portions of the channel 31 and sash opposite the same are apertured at 36. When the carrier block 28 is shifted upwardly in the channel 31 against the yielding resistance of 95 the spring 29, the rounded upper free end of the finger 26 will be cammed laterally out through the side aperture 36 by the beveled face 35 of the cam block 34, as clearly shown in Fig. 5, and, when the carrier block 28 is shifted downwardly 100 by the action of the spring 29, the finger 26 will be retracted, as shown in Fig. 6. The block 28 is provided at its lower end with a threaded bore 37 in which the upper threaded end of a long vertically extending rod 38 is screwed. The rod 105 38 extends downwardly within the hollow side of the sash and emerges at the bottom through a hole 39 in the adjacent end of the rubber sealing strip 33. The lower end 40 of the rod is preferably provided with a kerf 41 to facilitate screwing 110

the rod into or out of the block 28 in effecting adjustment of the same. The end 40 of the rod is adapted to engage with and be actuated by the sill 24 at the time that the sash seats against the sill. When the rod 39 is forced upwardly in the side of the sash by the downward movement of the latter in seating against the sill, the finger 26 will be forced laterally against the opposed face of a vertically extending member 42 associated with the guide strip 16, causing the sealing strip 17 to be pressed snugly against the opposed wall 18 of the side of the frame, all as clearly shown in Figs. 2 and 3.

From the foregoing, it will be understood that the sash 10 may be raised and lowered without effort in the grooved guides provided at the sides of the frame 11, and that, when the sash bottoms against the sill 24, the lower ends 40 of the rods 39 will be forced upwardly in the sides of the sash and will cause the fingers 26 to project laterally from the sides, thereby forcing the sash outwardly against the outer side walls of the guides. The fingers 26 of the sash-tightening devices are preferably located near the upper ends of the sides of the sash in order to exert pressure primarily on the upper portion of the sash, especially when locks 43 of the well known throw-over type are mounted on the bottom rail 22 of the sash. The locks 43 have no connection at all with the novel sash-tightening devices 25 of the invention but are merely used in the ordinary way, the noses 44 on the ends of the rock-bolts of the locks being intended to project under spring pressure into engagement with rack strips 45 housed within the lower portions of the guide strips 16.

In those window constructions wherein the sash-tightening devices 25 are used alone without the supplemental throw-over action of locks at the bottom of the sash, the locations of the devices 25 might be lowered, or else two of the fingers 26, connected together for simultaneous operation, might be used at each side of the sash, all for the purpose of obtaining the most advantageous distribution of the pressure on the sides of the sash outwardly against the sides of the frame.

The tightening devices 25 do not interfere in the least with the raising of the sash, releasing immediately as soon as upward pressure is brought to bear on the sash. The devices 25 may be easily adjusted by merely raising the sash and turning the rods 39 with a screw driver in either direction. If, in connection with some particular window construction, a small amount of projection of the fingers 26 laterally is sufficient to tighten the sash against the guides, then the rods 39 will be screwed inwardly in the blocks 28 into positions wherein the lower ends of the rods will project only a short distance below the rubber sealing strip 23 on the bottom rail of the sash. If, on the other hand, a large amount of projection of the fingers 26 is necessary in order to obtain a tight fit, the rods 39 will be screwed outwardly a corresponding distance. As will be noticed, the devices 25, although readily accessible for adjustment, are concealed by the guides.

In Figs. 8 to 10 inclusive, a somewhat different application of the invention is illustrated. In those views, the sash-tightening devices 46 are shown as being housed within the detachable guide strips 47 instead of within the sides 48 of the sash. The vertically extending rods 49 which act to force the upper ends of the fingers laterally into engagement with the sash, are pivotally connected at their lower ends to small levers

51 near the sill 52. The levers 51 are fulcrumed at 53 and are provided with hook-shaped ends 54 which project laterally into positions directly beneath the sash. When the sash seats against the sill, the bottom rail 55 of the sash will engage with and depress the ends 54 of the levers 51, causing the fingers 50 to force the sash outwardly into sealed engagement with the sides 56 of the frame.

I claim:

1. In window construction, a frame provided with vertically extending guides at the sides thereof, a sash slidably mounted in the guides, a pair of laterally projectible members housed within the sides of the sash for pressing the latter against corresponding sides of the guides when the sash is closed, and a pair of operating rods for the members extending downwardly therefrom into positions beneath the bottom rail of the sash for engagement with the sill of the frame when the window is closed, said rods causing the laterally projectible members to press the sash tightly against the guides when forced back up into the sash by engagement with the sill into positions flush with the bottom rail of the sash.

2. In window construction, a frame provided with vertically extending guides at the sides thereof, a sash slidably mounted in the guides, projectible means adjacent the upper portion of the sash for pressing the sash against corresponding sides of the guides, and means adjacent the lower portion of the sash connected with said first mentioned means for projecting the latter, said second mentioned means being operated automatically by the movement of the sash relative to the frame to project said first mentioned means when the sash reaches its closed position.

3. In window construction, a frame provided with vertically extending guides at the sides thereof, a sash slidably mounted in the guides, a pair of laterally projectible members housed within the sides of the sash above the bottom of the latter for pressing the sash against corresponding sides of the guides when projected, and vertically movable members projecting from the bottom of the sash and connected within the same to the projectible pressing members for automatically projecting the latter upon engagement with the sill of the frame.

4. In window construction, a frame provided with vertically extending guides at the sides thereof, a sash slidably mounted in the guides, movable sash tightening members, spring means for causing said members to assume inoperative positions while the sash is being raised or lowered, and positive means for automatically causing said members to assume operative positions at the instant that the sash bottoms on the sill of the frame.

5. In window construction, a frame provided with vertically extending guides at the sides thereof, a sash slidably mounted in the guides, sash tightening members movably mounted in the side rails of the sash, means for causing said members to assume inoperative positions while the sash is being raised or lowered, and means for automatically causing said members to assume operative positions at the instant that the sash bottoms on the sill of the frame.

6. In window construction, a frame provided with vertically extending guides at the sides thereof, a sash slidably mounted in the guides, movable sash tightening members, means for causing said members to assume inoperative positions while the sash is being raised or lowered, means

for automatically causing said members to assume operative positions at the instant that the sash bottoms on the sill of the frame, and manually adjustable means for varying the time of operation of said last mentioned means with respect to the position of the sash in the frame.

7. In window construction, a frame provided with vertically extending guides at the sides thereof, a sash slidably mounted in the guides, movable sash tightening members, means for causing said members to assume inoperative positions while the sash is being raised or lowered, means for automatically causing said members to assume operative positions at the instant that the sash bottoms on the sill of the frame, and manually adjustable means accessible from be-

neath the bottom rail of the sash when the latter is raised for varying the time of operation of said last mentioned means with respect to the position of the sash in the frame.

8. In window construction, a frame provided with hollow vertically extending guides at the sides thereof, a sash slidably mounted in the guides, sash tightening members movably mounted in the hollow guides, spring means for causing said members to assume inoperative positions while the sash is being raised or lowered, and positive means for automatically causing said members to assume operative positions at the instant that the sash bottoms on the sill of the frame.
